UNITED STATES PATENT OFFICE.

PAUL W. GRUENER AND GEORGE W. HENRY, OF NEW YORK, N. Y.

CLASP.

SPECIFICATION forming part of Letters Patent No. 783,782, dated February 28, 1905.

Application filed March 16, 1904. Serial No. 193,425.

To all whom it may concern:

Be it known that we, PAUL W. GRUENER and GEORGE W. HENRY, citizens of the United States, and residents of the borough of the Bronx, in the city and State of New York, have jointly invented certain new and useful Improvements in Clasps, of which the following is a specification.

This invention relates to the class of clasping devices, and particularly to such devices so constructed and adapted as to be applied for clasping shoe-laces in order to avoid the necessity of tying them.

The object of the invention is to provide an ornamental clasp which will embrace and hold the ends of the laces firmly and which may be readily unhooked or unclasped by a proper manipulation of the laces when the shoe is to be removed.

The specific features of the construction of the clasp and the manner of using the same will be fully hereinafter set forth, and the novel features carefully defined in the claims.

In the accompanying drawings, which illustrate an embodiment of the invention, Figure 1 is a perspective view showing a shoe with the clasp applied to and clasping the laces thereof. The other views show the clasp detached. Fig. 2 is an under side view of the clasp. Fig. 3 is a longitudinal section at line x^3 in Fig. 2, showing it closed. Fig. 4 is a similar view to Fig. 3, but with only the body of the clasp in section. Fig. 5 is a longitudinal section showing the clasp open. Fig. 6 is a cross-section, on a larger scale than Figs. 2 to 5, illustrating the clamping of the shoe-laces.

In Fig. 1, A designates a shoe, B the shoe-laces, and C the clasp as a whole. This figure shows the flat laces formed into bows and gripped by the clasp, the laces not being tied. Referring to the other figures, which show the construction of the clasp on a larger scale, 1 designates the ornamental face-plate of the clasp, which may be of metal, as silver, and chased or ornamented in any way desired. Within this face-plate is a base-plate 2, which may also be of metal, as brass, for example. The base-plate is secured to the face-plate in some convenient manner. As herein shown, 50 the thin metal of the face-plate is turned over

the edge of the base-plate so as to embrace and bind it. As represented in the drawings, the body of the clasp, formed by the plates 1 and 2, is of oblong form, rounded at the ends and has a concavo-convex contour. On the 55 inner or concave face of the base-plate are two bearing-lugs 3, in which is hinged a clasping-jaw 4. This jaw is mounted to be thrown open by the arm 5 of a coil-spring 6, mounted on the base-plate. The end of this arm 5 engages at 7 an aperture in the jaw 4, and when the jaw is closed the arm enters into an elongated slot 8 in the jaw, for a purpose to be hereinafter explained. When the jaw 4 is closed against the pressure of the spring, a 60 latching-keeper 9 in its free end engages a stud 10 on the base-piece and holds the jaw closed. It may be explained here that the hinge-pin 11, about which the jaw turns, engages slightly-slotted bearings (seen at 3^a in Fig. 5) in the lugs 3 and may be tightly fitted in hinging-lugs 4^a on the jaw, also that back of the hinge on the jaw 4 is a curved spring 4^b, which bears on a suitable lug 2^a on the base-plate. The effect of this is that the jaw 65 has a little endwise movement at the hinge and the spring 4^b tends to press it toward the catch-stud 10. Consequently when the jaw 4 is closed a bevel at 9^a thereon presses on and wipes over the stud 10, and pressure on the jaw moves the latter endwise until the stud 10 engages the keeper 9, when the spring 4^b pushes the jaw endwise until the stud fully 70 enters the undercut portion of the keeper. The disengagement or unlatching is effected 75 by pushing the jaw endwise toward the hinged end thereof.

In applying the clasp the laces B are drawn up snugly, flattened, and smoothed, the ends folded over to form bows and the clasp applied in such a manner that the laces will be embraced between the spring-arm 5 and the jaw 4. The jaw is then closed and latched, when the clasping-arm 5 will press the laces into the slot 8 in the manner seen in Fig. 6, 90 bending them into the slot and binding them tightly. To disengage the clasp, if the body of the latter be held between the thumb and finger and the laces be drawn sidewise toward the hinge the jaw will be shifted endwise and 95 100

unlatched so that the spring-arm can throw it open.

Obviously the body of the clasp may have other shapes or contours than that shown and 5 the base-plate and face-plate may be integral or of one piece. The purpose in making the body of two pieces is that the thin face-plate may then be of silver or gold and the heavier base-plate of a cheaper metal. The jaw 4 will 10 have, by preference, shoulders at 12 12, between which the laces lie when they are clasped. In order also that the laces may be made to embrace the clasping-arm 5 to a good extent when the jaw 4 is closed, as seen in 15 Fig. 6, the body portion of the jaw is hollowed on its under side at the point where the longitudinally-extending slot 8 therein is situated. This provides a more effective grip on the laces. The construction should be of 20 such a character that the arm 5 will press the laces in between parts of the jaw, as clearly shown.

As it may be desirable to have the clasp secured to the shoe so that it will not become 25 lost or mislaid and so, also, that it may always be in place convenient for use, there is or may be on the free end of the jaw 4 an apertured lug 13, by which the clasp can be secured to the eyeleted flap of the shoe with a cord or 30 the like.

Having thus described our invention, we claim—

1. A clasp for laces having a body, a clasping-jaw hinged thereto and slidable longitudinally for latching, a spring which moves the 35 jaw endwise, a latch device for securing the jaw when closed, and another spring with a clasping-arm which throws the jaw open and which presses the laces up to the jaw when the 40 latter is closed.

2. A clasp, having a body, a clasping-jaw hinged thereto and provided with a longitudinally-extending slot 8, means for securing the

jaw when closed, a spring for throwing the jaw open, and a clasping-arm 5 on said spring 45 adapted to enter into said slot 8 only when the jaw is closed.

3. A clasp for laces, having a body, a clasping-jaw hinged thereto and slidable longitudinally for latching, a spring which moves the 50 jaw endwise when unlatched and open, a latch device which secures the jaw when closed, and another spring, with a clasping-arm, which throws the jaw open, said arm being so disposed as to press the laces against the jaw when 55 the latter is closed.

4. A clasp for laces, having a body, a clasping-jaw hinged thereto and having a long slot 8 in its body portion, means for securing the jaw when closed, and a spring for throwing 60 the jaw open, said spring having a clasping-arm which extends longitudinally under the body portion of the jaw when the latter is closed and along the slot 8 therein, the end of said arm engaging the jaw near the hinging- 65 point of the latter.

5. A clasp, having a body provided with slotted hinging-lugs 3, a latching-stud 10, and a stud 2^a, a jaw 4, provided with hinging-lugs 4^a, a spring 4^b, a keeper 9 to engage the stud 70 10, and a beveled face 9^a adjacent to the keeper, a pin 11, hinging the jaw to the body, and a spring 6 on the body and provided with an arm 5, the free end of which bears on the jaw to throw it open, said arm being adapted to 75 enter an elongated slot in the jaw when the latter is closed.

In witness whereof we have hereunto signed our names this 12th day of March, 1904, in the presence of two subscribing witnesses.
